UNITED STATES PATENT OFFICE.

MARCUS O. ANTHONY, OF ENGLEWOOD, NEW JERSEY, ASSIGNOR TO STOLLWERCK BROTHERS,
OF NEW YORK, N. Y., A CORPORATION OF NEW YORK.

COIN-CONTROLLED MECHANISM FOR VENDING-MACHINES.

No. 917,986.

Specification of Letters Patent. Patented April 18, 1909.

Application filed March 22, 1907. Serial No. 323,920.

To all whom it may concern:

Be it known that I, MARCUS O. ANTHONY, a citizen of the United States, residing at Englewood, in the county of Bergen and State of New Jersey, have invented certain new and useful Improvements in Coin-Controlled Mechanism for Vending-Machines, of which the following is a full, clear, and exact specification:

10 The invention relates generally to coin-controlled mechanism, and particularly to an improved device for detecting and rejecting spurious coins or so-called "slugs" or "blanks," such as are sometimes used for 15 fraudulently operating vending machines.

Various devices have been heretofore tried for preventing the improper manipulation of a vending machine by means of blanks. These prior devices depend, as far as I am 20 aware, upon the diameter, thickness, weight, magnetic qualities, and jumping or bounding properties of the blank, and if a blank be employed of the proper size and kind, even though it fail to resemble a genuine coin in 25 every minute particular, the vending machine can often be worked.

My improvements depend for their operation upon a certain peculiarity in the shape of genuine coins, which is seldom if ever 30 found in a slug or blank and which, if it were attempted to imitate the same in a slug or blank, would render the latter too expensive to be used with profit. This peculiarity in 35 the shape of genuine coins which I utilize, is the milled or raised edge which renders a genuine coin thicker at its extreme edge or perimeter than at the portions inside the edge.

While I have illustrated and described 40 herein the preferred means of carrying my invention into operation, I desire it to be understood that other means may be employed, and I therefore do not limit myself to the precise construction disclosed, as changes 45 and modifications thereof can be made within the scope of the claims without departing from the spirit of my invention.

In the accompanying drawings forming 50 part of this specification, Figure 1 is a view in elevation with the cover of the casing removed, showing one of the locking devices in operative position to hold the coin-carrier against movement. Fig. 2 is a view similar to Fig. 1, showing the other of the locking devices in operative position. Fig. 3 is a sec-

tion taken on the line 3—3 of Fig. 6. Fig. 4 is a section taken on the line 4—4 of Fig. 6. Fig. 5 is a section taken on the line 5—5 of Fig. 3. Fig. 6 is a view similar to Figs. 1 and 2, showing the coin-carrier in position to receive a coin or blank, and locking devices held in inoperative position by their engagement with the inner wall of the casing. Fig. 7 is an enlarged sectional view similar to Fig. 5, and partially broken away to show the position of the coin after it has been entirely inserted, and after the coin-carrier has been partially rotated. Fig. 8 is a view similar to Fig. 5 showing the coin-carrier after it has been rotated, and illustrating the position of the coin ejector when about to eject the coin. Fig. 9 is a view similar to Fig. 1, showing the position of the locking devices when the coin-carrier contains a genuine coin, and has been partially rotated. Fig. 10 is a sectional view, 75 on a reduced scale, taken on the line 4—4 of Fig. 6, the coin-carrier being removed. Fig. 11 is a sectional view through an ordinary coin. Fig. 12 is a perspective view, on a reduced scale, of the coin-carrier.

Like reference characters indicate corresponding parts in the different figures of the drawing.

The reference letter A indicates a casing which preferably is annular in form and is 80 provided at one side with a removable plate or cover 1. The casing A, as shown particularly in Fig. 8, is provided at one side with an opening or coin-entrance 2, and at the opposite side with a coin-exit 3.

Mounted for rotary movement inside the casing A is a coin-carrier B (shown in detail in Fig. 12), which preferably is in the form of a circular plate adapted to fit nicely within the casing A and to rest against one side 90 thereof, as shown in Fig. 3. The coin-carrier B is provided in the side thereof which rests against the bottom 4 of the casing A, with a coin chamber 5 having an entrance portion 6. When the rotary carrier B is in the 95 position illustrated in Fig. 5, so that the entrance portion 6 of the coin chamber 5 is opposite the coin entrance 2, and a coin such as 7 is inserted through the coin entrance 2, said coin will be held partially in the coin 100 chamber 5 and partially in the entrance portion 6, as indicated by the dotted lines in Fig. 5, so that when the carrier B is rotated in the direction of the arrow, the coin will be carried around through the casing A and dis-

charged through the coin-exit 3 into any suitable coin receptacle not shown.

For the purpose of permitting the coin-carrier B to be freely rotated within the casing A to convey a coin from the coin entrance 2 to the coin exit 3 when a genuine coin is inserted, and for locking said carrier B against rotation in the casing A when a slug, blank, or spurious coin is inserted, the following mechanism preferably is employed. Extending through suitable perforations in the carrier B is a pair of contact members 8 and 9, the contact ends of which, as shown in Figs. 3 and 5, terminate or project into the entrance portion 6 of the coin opening 5. The proper action of the contact members 8 and 9 depends upon the peculiar shape of a genuine coin as distinguished from the usual shape of a slug or blank; this peculiar shape of a genuine coin residing in the edge or perimeter 10 of a genuine coin, as shown in Fig. 11, which is thicker than the central portion 11 of the coin, so as to produce in effect a raised flange or border on each side of the coin. The contact member 8 preferably is formed with a flat end, which is adapted to contact with the thick perimeter of the coin 7, as shown in Fig. 3, and the contact member 9 preferably is formed with a pointed end which is adapted to contact with the thin central portion of the coin 7, preferably at a point just inside the thickened perimeter thereof. If a genuine coin be inserted, as shown in Fig. 3, the contact members 8 and 9, together with the mechanism operated thereby as hereinafter described, will permit the carrier B to rotate and discharge the coin through the coin exit 3, but if a slug or blank be inserted which is equal in thickness, throughout its entire area, to the thickest portion or edge of a genuine coin, the contact member 9 will bear against the thick slug, and will thereby be prevented from moving to its accustomed position in the entrance portion 6, whereby the mechanism connecting with the contact member 9 will prevent the rotation of the carrier B, and if a blank be employed which is of a thickness equal to the thin or center portion of a genuine coin, the contact member 8 will move too far into the entrance portion 6, and will lock the carrier B against rotation.

The mechanism operated by the contact members 8 and 9 to control the action of the carrier B, is shown particularly in Figs. 1, 2, and 6. This mechanism comprises a lever 12, which is fulcrumed upon a pin 13 extending through suitable ears or lugs 14, connected with the carrier B, and a similar lever 15 fulcrumed upon a pin 16, extending through lugs 17, connected with the carrier B. The outer end of the pointed contact member 9 is bent at an angle and extends through a suitable perforation in the lever 12, so that the movement of the contact

member 9 will be communicated to said lever, and the outer end of the blunt contact member 8 is similarly bent and extends through a perforation in the lever 15, so that the movement of said contact member 8 is communicated to said lever 15. The levers 12 and 15 are provided with suitable springs 18 and 19, which are formed preferably of resilient wire bent to form a series of coils which are wound about the pivot pins of the levers 12 and 15 as shown, and each spring is also provided with a pair of arms, one of which bears outward against the lever, and the other against the surface of the carrier B, so that the action of the springs 18 and 19 is to force one end of each lever outward, and consequently throw the other end of each lever inward, whereby the contact members 8 and 9 are pressed in a yielding manner against the coin 7 after it has been inserted into the carrier. Pivotaly mounted at 20 upon the rotary carrier B is a pair of hooks or locking devices 21 and 22, the locking devices 22 in Fig. 6 lying immediately under the locking device 21. Each of the locking devices 21 and 22 is provided at one end with a hook portion 23, and at the opposite end with a suitable engaging surface or tail portion, the tail portion of the locking device 21 being adapted to be engaged by the lever 15, and the tail portion of the locking device 22 being adapted to be engaged by the lever 12.

As shown in Figs. 1 and 2, a pair of flat springs 24 and 25 are suitably connected with a lug or block 26 mounted on the carrier B, the spring 24 bearing against the locking device 21, and the spring 25 against the locking device 22, said springs tending to throw the hook portions of said locking devices outward. After the carrier B has been rotated a short distance in the direction of the arrow in Figs. 1 and 2, either or both of the locking devices are adapted to engage a recess 27 formed in the inner wall of the casing A, so as to lock the carrier B against further rotation.

As hereinafter more clearly described, the carrier B is intended to be rotated by a suitable handle after the coin has been inserted. When the parts are in the position illustrated in Fig. 6, a coin can be inserted through the coin-entrance 2 into the coin-carrier B. In this position the hook portions 23 of the locking devices 21 and 22 bear against the inner wall of the casing A, and the tail portions of said locking devices are in such position that the levers 12 and 15 can rock freely without striking said tail portions. If the coin which is inserted be genuine, the contact members 8 and 9 will move the levers 12 and 15 into such position that the lever 12 will lie in position to be engaged by the tail member of the locking device 22, and the lever 15 in position to engage the tail portion of the locking device 21. If the carrier B be now

rotated, the engagement of the levers with the locking devices will prevent the springs 23 and 24 from throwing said locking devices outward to engage the recess 27, and the carrier B can thus be freely rotated. If, however, a thin or a thick slug is inserted, one or the other of the levers 12 and 15 will be moved to such position that it will not engage the tail portion of the adjacent locking device, for which reason one of the locking devices will be permitted to be forced outward by its spring and will thus engage the recess 27 and lock the carrier against rotation. This action is illustrated in Figs. 1 and 2. In Fig. 1 a thick slug has been inserted. Therefore, as the slug is not formed with a central thin portion, the contact member 9 cannot move inward the usual distance, and the lever 12 fails to engage the tail of the locking device 22. In Fig. 2 a thin slug has been inserted. Therefore, the contact member 8, failing to be stopped by the usual thick rim of a coin, moves inward too far, and the lever 15 consequently does not engage the tail of the locking device 21.

For the purpose of holding the coin-carrier B in position against the bottom 4 of the casing A, a number of pins 30, 31, and 32 are employed. These pins extend through the casing A and project over the edge of the coin-carrier B so as to hold it in position.

In order to prevent the contact members 8 and 9 from retarding the entrance of the coin, and for causing said contact members to engage the coin only after it has been completely inserted, the pins 31 and 32 are formed with beveled or inclined cam faces, and the ends of the levers 12 and 15 near the contact members 8 and 9 are beveled or inclined, as shown at 33 and 34 in Fig. 3, so that when the coin-carrier B is turned to the position shown in Fig. 6, in which position the entrance-portion 6 of the coin-chamber 5 of the carrier B registers with the coin-entrance 2 in the casing A, the inclined faces 33 and 34 of the levers 12 and 15 have ridden up the cam faces of the pins 31 and 32 in such manner that the contact members 8 and 9 have been drawn outward (or to the left in Fig. 3) from the entrance-portion 6, so as not to hinder the entrance of the coin. Then when the coin-carrier is rotated in the direction of the arrow in Fig. 6, the levers 12 and 15 move off the cam surfaces of the pins 31 and 32, and the springs 18 and 19 throw the contact members 8 and 9 into engagement with the coin, with the result, as previously described, that if the coin be genuine, both devices 21 and 22 will be locked, but if it be a slug, one or the other of the devices 21 and 22 will be free to engage the recess 27 and prevent further rotation of the carrier B.

The means for rotating the coin-carrier B and for ejecting the coin or slug preferably are arranged as follows: The numeral 35 in-

dicates a shaft which extends through the casing A and is provided with a handle or knob 36. Rigidly mounted on the shaft 35 is a cam-shaped ejector 37 which, as shown in Figs. 4, 5, and 6, is disposed within the coin chamber of the carrier B. The ejector 37 is capable of loose or independent movement between a pair of limiting pins 38 and 39 secured to the carrier B and projecting into the coin-chamber 5 (Figs. 7 and 8). Surrounding the shaft 35 is a coil-spring 40 which, as shown in Fig. 3, is secured at 41 to the shaft 35, and at 42 to the casing A. The coil-spring 40 serves to rotate the shaft 35 and the ejector 37 in a direction opposite to the arrow in Fig. 5, so as normally to hold the coin-carrier B and the ejector 37 in the position illustrated in Fig. 5. When a coin such as 7 is inserted, it engages the edge of the ejector 37 and swings it in the direction of the arrow, so that it moves out of engagement with the limiting pin 39. If the person who inserted the coin then grasps the knob 36 of the shaft 35 and rotates the same in the direction of the arrow in Fig. 5, the ejector 37, by its engagement with the limiting pin 38 will rotate the carrier B in the direction of the arrow, thus carrying the coin 7 around, against the tension of the coil-spring 40, from the position shown in Fig. 5 to that shown in Fig. 8. Of course, as previously explained, the carrier B can be rotated in this manner only when a genuine coin has been inserted. As soon as the carrier B has reached the position illustrated in Fig. 8, if the knob 36 be released, the action of the coil-spring will move the cam or ejector 37 in the direction of the arrow in Fig. 8, thus ejecting the coin 7 through the coin-exit 3, and causing the ejector 37 to engage the limiting pin 39 so that the continued action of the coil-spring 40, after the coin has been ejected, will rotate the carrier B back to the position shown in Fig. 5, to be in readiness to receive another coin.

The rotation of the shaft 35 in the direction of the arrow in Fig. 5 can be utilized in any suitable manner to eject a package of chewing gum or chocolate, or the like, from the vending machine with which the casing A is connected. This package-ejecting mechanism can be connected with the shaft 35 in any suitable manner, but as it forms no part of the present invention, its specific illustration and description is deemed to be unnecessary herein.

For the purpose of preventing the shaft 35 and the coin-carrier B from being reversely rotated in the direction opposite to the arrow in Fig. 5 after the coin has been inserted, and before it has been discharged through the coin-exit 3, the casing A is provided with a plurality of shallow recesses 43, whereby, after a genuine coin has been inserted, and the shaft 35 has been rotated in the direction 130

of the arrow far enough to eject a package of chewing gum or the like without discharging the coin through the coin-exit 3, if it be attempted to rotate the shaft backward so as to secure a second package of material, the cam 37 will throw the coin outward into engagement with one of the recesses 43, thus locking the carrier B against reverse rotation.

It sometimes happens that a vending machine will be clogged by the insertion of bits of paper and the like through the coin-entrance 2. In order to provide effective means for readily removing any such bits of paper or other clogging material, the casing A is formed in its bottom 4 adjacent the coin-entrance 2 with an opening 45 (Fig. 10), and the shaft 35 has rigidly secured thereto, so as to rotate therewith, a protecting plate 46. The protecting plate 46 is provided with a circular opening 47 which, when the parts are in the position illustrated in Fig. 5, is adapted to register with the opening 45 in the bottom 4 of the casing A, so that an instrument, such as a pin, or the like, can be inserted through the openings 47 and 45 to pick out any paper or other clogging material in the machine. As soon as the knob 36 is rotated, the opening 47, in the protecting plate 46, moves out of register with the opening 45 in the casing A, and thus shuts off access to said casing.

From the foregoing description in connection with the drawing, it will be apparent that the device of the present invention is provided with means controlled by the different thicknesses of a genuine coin for regulating its operation.

The improved device is strong, simple, durable, and inexpensive in construction, as well as thoroughly efficient in its operation.

What is claimed is:

1. A coin-controlled device having contact means adapted to engage a coin or blank at different distances from the center thereof, and movable in the plane of movement of the coin or blank, and independent locking means operated by the contact means and movable in opposite directions to lock the device.

50 2. A coin-controlled device having oppositely movable means controlled by the surface elevations of different portions of a coin or blank, for controlling the operation of the device, and means for preventing relative movement between said contact means and the coin or blank.

3. A coin-controlled device having a plurality of contact members, one of said members extending normally a slight distance in advance of the other, and locking means connected with said contact members and movable to locked position upon a movement of one of said contact members in one direction, or a movement of the other of said contact members in the opposite direction.

4. A coin-controlled device having contact members adapted to engage different surface portions of a coin or blank, means for preventing relative movement between the contact members and the coin or blank while in engagement with each other, and a plurality of locking means operated by said contact members for controlling the operation of the device, one of said locking means being movable in one direction to locked position and the other of said locking means being movable in an opposite direction to locked position.

5. A coin-controlled device having a plurality of contact members, one of said members projecting normally in advance of the other when in contact with a coin, and means operated by an advance movement of one contact member or a rearward movement of the other contact member for locking the device.

6. A coin-controlled device having a plurality of contact members, means for causing one of said contact members to extend normally a slight distance in advance of the other, and a plurality of locking means movable in opposite directions to locked position connected with said contact members, said locking means being in unlocked position when one of said contact members is slightly in advance of the other, and being in locked position when the relative position of said contact members is changed.

7. A coin-controlled apparatus having locking members movable in opposite directions to locked position, and contact members for controlling said locking members, said locking members being in inoperative position when one of said contact members projects slightly in advance of the other, and being in locked condition when this relative position of the contact members is changed.

8. A coin-controlled apparatus having a plurality of independent locking members movable in opposite directions to locked position, and a contact member for each of said locking members, one of said contact members projecting slightly in advance of the other of said contact members, when said locking members are in unlocked position.

9. A coin-controlled apparatus having a plurality of locking means movable in opposite directions to locked position and a plurality of contact members connected with said locking means, one of said contact members projecting slightly in advance of the other when said locking means is in unlocked position.

10. A vending machine having a plurality of coin-operated means movable in opposite directions to locked position for rendering the device inoperative when a coin or blank having different surface elevations from a genuine coin is used.

11. A coin-controlled apparatus having a plurality of coin contact members, one pro-

- jecting relatively in advance of the other, and means operated by an advance movement of one contact member or a rearward movement of the other contact member for controlling the operation of the apparatus.
12. A coin-controlled device having a casing, a movable member in the casing, a pair of contact members, and means for permitting the operation of said movable member when one of said contact members is relatively in advance of the other, and for preventing the operation of said movable member when one of said contact members is moved forward or the other backward.
13. A coin-controlled device having a casing, a movable carrier in the casing, coin-contact members and a plurality of locking means movable in opposite directions to locked position connected with said contact members for locking the carrier, one of said contact members projecting slightly in advance of the other when the locking means are in unlocked position.
14. A coin-controlled device having a movable coin-carrier, locking means movable in opposite directions to locked position for said coin-carrier, and contact members movable with the coin-carrier and connected with said locking means, one of said contact members projecting slightly in advance of the other when said locking means is in unlocked position.
15. A coin-controlled device having a casing, a movable coin-carrier, means controlled by the thickness of different portions of a coin or blank for controlling the movement of the coin-carrier, an ejector adapted to eject either a coin or a blank, and means for operating the ejector to cause it to move the coin-carrier.
16. A coin-controlled device having a movable coin-carrier, and locking means mounted on the coin-carrier and movable in opposite directions to locked position and controlled by the thickness of different portions of a coin or blank for controlling the movement of the carrier.
17. A coin-controlled device having coin-receiving means, a plurality of contact members, means for holding the contact members in operative position until the coin is inserted, means for causing the contact members to engage the coin after it has been inserted, means for preventing relative movement between the coin and contact members while in engagement with each other, and locking means movable in opposite directions to locked position controlled by the contact members for determining the operation of the device.
18. A coin-controlled apparatus having a movable coin-carrier, contact members mounted on said coin-carrier and movable therewith, and locking members movable in opposite directions to locked position oper- ated by said contact members for controlling the operation of the coin-carrier.
19. A coin-controlled device having a movable carrier, locking means movable in opposite directions to lock said carrier, contact members connected with said locking means, one of said contact members projecting in advance of the other when said locking means is in inoperative position, and means for preventing reverse movement of the carrier after a coin has been received.
20. A coin-controlled device having a rotary coin-carrier, and oppositely movable means controlled by the thickness of different portions of a coin or blank for controlling the movement of the rotary coin-carrier.
21. A coin-controlled device having a rotary coin-carrier, and oppositely movable means controlled by the thickness of different portions of a coin or blank for permitting movement of the rotary coin-carrier upon the entrance of a coin, and for preventing movement of said carrier upon the entrance of a blank.
22. A coin-controlled device having a casing provided with a coin-entrance and a coin-exit, a plurality of locking devices movable in opposite directions to locked position and adapted to prevent the operation of the coin-controlled device, a contact member connected with each of said locking devices, one of said contact members projecting in advance of the other when the locking devices are in inoperative position, and means for causing said contact members to engage a coin or blank.
23. A coin-controlled device having a casing, a movable coin-carrier in said casing, locking devices mounted on said coin-carrier and movable in opposite directions to locked position, and contact members connected with said locking devices and adapted to engage different surface portions of a coin or blank, one of said contact members projecting in advance of the other when the locking devices are in inoperative position.
24. A coin-controlled device having a movable carrier locking devices movable in opposite directions to locked position, and contact members connected with the locking devices and movable with the carrier, one of said contact members projecting in advance of the others when the locking devices are in unlocked position.
25. A coin-controlled device having a movable coin-carrier, locking devices movable in opposite directions to locked position mounted on said coin-carrier, and adapted to lock the same against movement, and contact members mounted on said coin-carrier and adapted to engage a coin or blank at different distances from the center thereof, said contact members being adapted to control the operation of said locking devices.
26. A coin-controlled device having means

controlled by the thickness of different portions of a coin or blank for receiving a coin and rejecting a blank, and mechanism for holding said controlling means in inoperative 5 position until the coin or blank has been completely inserted into the coin-controlled device.

27. A coin-controlled device having contact members adapted to engage a coin or 10 blank at different distances from the center thereof, means controlled by said contact members for permitting the passage of a coin and preventing the passage of a blank, and means for holding said contact members out 15 of engagement with a coin or blank until said coin or blank has been completely inserted, whereby to prevent the contact members from retarding the initial insertion of the coin or blank.
28. A coin-controlled device having a casing 20 provided with an entrance, and an opening adjacent said entrance for cleaning the same, and a rotary coin-carrier provided with an opening adapted to register with the opening 25 in said casing only when said coin-carrier is in one position.

29. A coin-controlled device having a casing, a movable coin-carrier, contact members mounted on the coin-carrier and adapted 30 to engage a coin or blank at different distances from the center thereof and movable with the coin carrier, levers connected with said contact members, and locking devices movable in opposite directions to locked position adapted to coöperate with said levers 35 for controlling the movement of said carrier.

30. A coin-controlled device having a casing, a movable coin-carrier in said casing, contact members mounted on the coin-carrier and adapted to engage a coin or blank at different distances from the center thereof and movable with the coin carrier, levers connected with said contact members, springs for yieldingly moving said contact 40 members into engagement with a coin or blank, and locking devices movable in opposite directions to locked position and coöperating with said levers and adapted to control the movement of said coin-carrier.

31. A coin-controlled device having a casing, a movable coin-carrier, contact members mounted on said coin-carrier and adapted to engage a coin or blank at different distances from the center thereof, levers mounted 45 on said coin-carrier and connected with said contact members, and locking devices movable in opposite directions to locked position mounted on said coin-carrier and coöperating with said levers to control the 50 movement of said coin-carrier.

32. A coin-controlled device having a casing, a movable coin-carrier, contact members mounted on the coin-carrier, and adapted to engage a coin or blank at different 55 distances from the center thereof, levers mounted

ed on the coin-carrier, and connected with said contact members, springs engaging said levers for throwing said contact members yieldingly into engagement with a coin or blank, locking devices mounted on said coin-carrier and having tail pieces adapted to be engaged by said levers, and springs for throwing said locking devices into operative position.

33. A coin-controlled device having a casing, 75 a movable coin-carrier, contact members adapted to engage a coin or blank at different distances from the center thereof, levers connected with said contact members, means coöperating with said levers for holding said contact members out of engagement with a coin or blank until the coin-carrier has made its initial movement, and mechanism coöperating with said levers for controlling the movement of said coin-carrier.

34. A coin-controlled device having a rotary coin-carrier, contact members adapted to engage a coin or blank at different distances from the center thereof, means for holding said contact members in inoperative 90 position until the coin-carrier has made its initial rotary movement, and means coöperating with said contact members for controlling the movement of said coin-carrier.

35. A coin-controlled device having a movable, coin-carrier, pivotally mounted locking means movable in opposite directions to locked position, and contact members mounted on the coin-carrier and adapted to engage a coin or blank at different distances from 100 the center thereof and movable with the coin carrier for controlling the action of said locking devices.

36. A coin-controlled device having a coin-carrier, and an ejector means to permit said 105 ejector to move independently of said coin-carrier, said ejector being adapted to move said coin-carrier and to eject coins or blanks.

37. A coin-controlled device having a coin-carrier provided with limiting pins, and an eccentric ejector capable of independent movement between said limiting pins, said ejector being adapted to move said carrier and to eject coins or blanks.

38. A coin-controlled device having a casing, a coin-carrier mounted for rotary movement in said casing and having a coin chamber provided with a coin entrance, limiting pins mounted on said coin-carrier within said coin chamber, and an eccentric ejector located in said coin-chamber and capable of independent movement between said limiting pins, said ejector being adapted to move said coin-carrier and to eject a coin or blank.

39. A coin-controlled device comprising a 115 casing having a coin-entrance and a coin-exit, a coin-carrier mounted for rotary movement in said casing, contact members mounted on the coin-carrier and adapted to engage a coin or blank at different distances from the 120

130

center thereof, mechanism coöperating with said contact members for controlling the movement of said coin-carrier, and an eccentric ejector capable of independent movement with respect to said coin-carrier, said ejector being adapted to move said coin-carrier and to eject a coin or blank.

40. A coin-controlled device comprising an annular casing having a coin-entrance, a coin-exit, and a plurality of shallow recesses adapted to receive the edge of a coin, a coin-carrier mounted for rotary movement in said casing, and having a coin chamber, a pair of limiting pins adapted to engage a coin or blank at different distances from the center thereof, a pair of contact members, a pair of spring-operated levers connected with said contact members, a pair of spring-operated locking devices adapted to be engaged by said levers, a pair of cam members projecting over the surface of said coin-carrier, and adapted to engage said levers for normally holding said locking devices out of engagement with a coin or blank, a spring-operated shaft extending through said casing, a cam-

shaped ejector mounted on said shaft and located in the coin-chamber of the coin-carrier between the limiting pins thereof, and a protecting plate mounted on said shaft and having an opening therein adapted to register 30 with a similar opening in said casing, the locking devices mounted on said coin-carrier being adapted to coöperate with a recess formed in the inner wall of said annular casing, substantially as described. 35

41. A coin-controlled device having a contact member adapted to engage a relatively thick portion of a genuine coin, and a contact member adapted to engage a relatively thin portion of a genuine coin, and means operated by said contact members for receiving a coin and rejecting a blank. 40

In testimony whereof, I have hereunto set my hand in the presence of two subscribing witnesses.

MARCUS O. ANTHONY.

Witnesses:

ADOLPH F. DINSE,
CHARLES A. SCHEUBER.
